DESIGN FOR A SOAP CAKE UNIT

Gordon D. Voorhis, Rhinebeck, N. Y., assignor to
Voorhis-Tiebout Company, Inc., Rhinebeck,
N. Y., a corporation of New York

Application August 20, 1940, Serial No. 94,518

Term of patent 14 years

To all whom it may concern:

Be it known that I, Gordon D. Voorhis, a citizen of the United States, residing at Rhinebeck, in the county of Dutchess and State of New York, have invented a new, original, and ornamental Design for a Soap Cake Unit, of which the following is a specification, reference being had to the accompanying drawing, forming part thereof.

In the drawing:—

Fig. 1 is a perspective view of a soap cake unit, showing my design; and

Fig. 2 is a perspective view of one of the cakes of soap which comprise the soap cake unit shown in Fig. 1.

I claim:

The ornamental design for a soap cake unit, as shown and described.
